ALL YEAR AIR CONDITIONING SYSTEM

George D. Kingsland, Minneapolis, Minn., and
 Joseph E. Robb, Topeka, Kans., assignors to
 Minneapolis-Honeywell Regulator Company,
 Minneapolis, Minn., a corporation of Delaware

Application June 6, 1934, Serial No. 729,252

20 Claims. (Cl. 236—1)

The present invention relates to an improved air conditioning system for all-year operation by means of which a space or building is cooled in the summer and is heated and humidified in the winter.

One of the objects of the present invention is the provision of an air conditioning system including steam operated heating means and steam operated cooling means which are supplied with steam from a single boiler or steam generator under the control of suitable thermostatic mechanism. The steam operated heating means preferably takes the form of steam radiators or heating coils and the steam operated cooling means is preferably in the form of a steam jet injector type of cooling apparatus.

Another object of the invention is the provision of an improved temperature changing system in which a temperature changer is operable to change the temperature in two different spaces, the temperature changer being controlled by the temperature prevailing in one of the spaces and the effect of the temperature changer on both of said spaces being controlled by a thermostat responsive to the temperature prevailing in the other of the spaces. In the preferred form of this phase of the invention, a temperature changer is intermittently operated by a thermostat located in one space and serves to heat a supply of air which is circulated to both of the spaces. A thermostat located in the other of the spaces serves to control the proportions of this circulated air which is circulated to each of the spaces.

A further object of the invention is the provision of an improved temperature control system for summer-winter operation by which the supply of outdoor air to a space to be controlled is varied from a minimum to a maximum and then again to a minimum upon a change in temperature in one direction during the summer and is varied only from a minimum to a maximum upon temperature changes in a single direction during the winter. In the preferred form of the invention, both of these thermostats are outdoor thermostats, the arrangement being such that in the summer the outdoor air is varied from a minimum to a maximum as the outdoor temperature rises from a value lower than that desired within the space to be controlled to the value desired in the controlled space and is then again reduced to a minimum as the outdoor temperature continues to increase whereas in the winter time the supply of outdoor air is varied from a maximum to a minimum as the outdoor temperature falls from some mild condition approxi-

mating the desired indoor temperature to a more severe outdoor temperature condition.

Another object of the invention is the provision of an improved system of control for a steam operated cooling means.

A further object of the invention is the provision of an improved heating system.

Further objects of the invention include the various features and functions of the system as a whole as well as the various features and functions of the various sub-combinations and parts thereof.

Other objects of the invention will be found in the detailed description, in the drawings, and in the appended claims.

For a better understanding of the invention, reference may be had to the following description and accompanying drawings, in which:

Fig. 1 is a diagrammatic showing of the complete control system, and

Fig. 2 is a diagrammatic showing of the control systems for the inlet air dampers and for the outlet air damper.

Referring first to Fig. 1 of the drawings, the system includes an air conditioning device, generally indicated at 10, which includes an air conditioning chamber 11. Located in the air conditioning chamber 11 is a preheating coil 12 and a reheating coil 13 which are supplied with steam from a steam boiler 14 by means of a pipe 15. A hand-operated shut-off valve 16 is located in pipe 15 and may be utilized to prevent the flow of steam to the preheating and reheating coils 12 and 13 during the summer time. The flow of steam to the preheating coil 12 is additionally controlled by means of an electrically operated valve 9 in a manner to be hereinafter described.

The boiler 14 is fired by a gas burner 17 which, in turn, is controlled by an electrically operated gas valve 18 that controls the flow of gas from a gas supply pipe 19 to the burner 17. A pilot burner 20, which is normally constantly burning, is supplied with gas by means of a pilot pipe 20a which communicates with the gas supply pipe 19 in front of the electrically operated gas valve 18. The primary controls for the gas valve 18 comprise a room thermostat 21 and an outdoor thermostat 22 herein indicated diagrammatically by mercury switches of well-known construction. The room thermostat 21 is provided with a pair of contacts 23 which close when the room temperature is at or below some predetermined minimum temperature, say 70° F. This room thermostat 21 is additionally provided with a second pair

- of contacts 24 which are closed when the room temperature is at or above said predetermined minimum temperature. The cold contacts 23 of the room thermostat 21 are the primary control 5 for the gas valve 18 when the apparatus is operating on the winter cycle as will hereinafter become evident whereas the hot contacts 24 thereof are the primary control for gas valve 18 when the apparatus is operating on the summer cycle.
- 10 The outdoor thermostat 22 is provided with a single pair of contacts 25 which open when the outdoor temperature decreases below the desired room or space temperature. A single pole, double throw manually operable summer-winter switch 15 comprises a switch arm 26, a winter contact 27 and a summer contact 28. The two thermostats 21 and 22 and this summer-winter switch cooperate in the control of a relay generally indicated at 29. This relay 29 comprises a relay 10 coil 30 which, upon energization, attracts an armature 31. When armature 31 is attracted, it moves a switch arm 32 from engagement with a contact 33 and into engagement with a contact 34. It likewise moves a switch arm 35 into engagement with a contact 36. When the relay coil 30 is deenergized so that armature 31 may return to the position shown in the drawings, switch arms 32 and 35 move from engagement with contacts 34 and 36 and switch arm 32 moves into engagement with contact 33. Power for relay 29 is supplied by the low voltage secondary 37 of a step-down transformer 38, having a high voltage primary 39 connected to suitable line wires. The gas valve 18 is additionally controlled by another 25 relay, generally indicated at 40, which comprises an energizing coil 41 and a bucking coil 42 that cooperate in the control of an armature 43. When armature 43 is attracted, it moves a pair of switch arms 44 and 45 into engagement with a pair of cooperating contacts 46 and 47, these 30 switch arms being out of engagement with contacts 46 and 47 when the armature 43 is in its normal unattracted position. The relay 29 contributes to the control of relay 40 which is also controlled by a high limit pressure control generally indicated at 48. This high limit pressure control comprises a pressure responsive element in the form of a bellows 49 which is connected to the steam pipe 15. Bellows 49 operates a pivoted 35 switch carrier 50 which supports a mercury switch 51. The mercury switch 51 is provided with a pair of low pressure contacts 52 which are closed when the pressure is low and with a pair of high pressure contacts 53 which are closed 40 when the pressure is high. This pressure responsive high limit control may take the form shown in Louis A. M. Phelan Patent No. 1,736,129 which issued November 29, 1929, and is preferably adjusted so the high pressure contacts 53 are closed when the pressure in steam boiler 14 attains some excessive value such as 15 lbs. per 45 square inch. The low pressure contacts 52 are preferably arranged to operate at some slightly lower value so there is a differential between the 50 operation of the high and low pressure contacts.
- 60 Power for relay 40 is supplied by the low voltage secondary 54 of a step down transformer 55, having a high voltage primary 56. The flow of power to the transformer 55 is controlled, among 65 other things, by a switch 57 which responds to the water level in the boiler in the usual and well-known manner. The pilot 20 is preferably provided with a safety device in the form of a bimetallic thermostatic element 58 which engages 70 a cooperating contact 59 whenever the pilot 20

is burning. This safety pilot comprised by element 58 and contact 59 also contributes to the control of gas valve 18.

The air conditioning chamber 11 is further provided with a cooling coil 60 which is supplied with a cooling medium that is cooled by means of a steam jet injector, generally indicated at 61. This fluid medium is transmitted from the steam jet injector 61 to the cooling coil 60 by means of pipes 62, 63 and 64 and by means of an electrically operated circulating pump 65. Energization of circulating pump 65 is controlled by a relay 66 which comprises a relay coil 67 and an armature 68 that moves a switch arm 69 into engagement with a contact 70 when the relay coil 15 67 is energized.

Air is circulated through the air conditioning device 10 by means of an electrically operated blower 71. This blower is controlled by a relay 72 which includes a relay coil 73, and an armature 20 74 that controls the movements of a switch arm 75 which cooperates with a contact 76. The relay 72 is controlled by means of a time switch 77 and a pressure responsive switch 78.

The time switch 77 comprises a motor having 25 an energizing winding 79 which operates a cam 80 through suitable reduction gearing (not shown). The cam 80 operates a pivoted switch carrier 81 that in turn supports a mercury switch 82. The arrangement is such that mercury switch 82 is closed during predetermined hours 30 of the day and is open at all other times. This time switch is herein disclosed inasmuch as the system herein illustrated has particular utility 35 in connection with office buildings and the like which are generally only occupied during the day time but it will be apparent that in buildings of other types where it is desired to condition the air for the full twenty-four hours, this time switch can be omitted.

The pressure responsive switching mechanism 40 78 is utilized, as will hereinafter become apparent, to supplement the action of the time switch 77 in order to prevent the building from reaching 45 too low a temperature during the night when the time switch 82 is opened and the system is operating on its winter cycle. This pressure responsive switching mechanism 78 includes bellows 83 which communicates with steam pipe 15 on the delivery side of shut-off valve 16. Bellows 50 83 operates a switch carrier 84 which in turn supports a mercury switch 85. The arrangement is such that the mercury switch 85 closes whenever the steam pressure is at or above some predetermined value say 5 lbs. per square inch. In 55 general arrangement, this switching mechanism 78 may also take the form shown in the above mentioned Phelan patent.

The air conditioning chamber 11 is further provided with a water spray 86 by which the air 60 passing therethrough may be humidified. This water spray 86 communicates with a water supply pipe 87 through an electrically operated water valve 88. Water valve 88 in turn is controlled, in part, by a humidostat 89 arranged to close 65 the circuit to water valve 88 when the relative humidity becomes too low.

The air conditioning device 10 is provided with an outdoor inlet duct 90 and a return air inlet duct 91 both of which communicate with the 70 air conditioning chamber 11. The flow of air through outdoor and return air inlet ducts 90 and 91 is controlled by a pair of dampers 92 and 93 in a manner which will be hereinafter explained in detail. The air conditioning device 75

10 is further provided with a pair of outlet ducts 94 and 95. Outlet duct 94 leads to the more general spaces to be controlled whereas outlet duct 95 leads to some special space which it is desired to control such as a recreation room in the basement, an auditorium, etc. The flow of air through these outlet ducts 94 and 95 is controlled by a mixing damper 96 which is operated in a manner, the details of which will be later disclosed.

10 Steam is supplied from the boiler 14 to the steam jet injector 61 by means of a pipe 97 which communicates with steam pipe 15. The flow of steam through pipe 97 is controlled by an electrically operated valve 98 that is supplied with power by the secondary 99 of a step-down transformer 100, having a high voltage primary 101. This valve 98, upon being opened, lifts a lever 102 that moves a mercury switch 103 supported thereby to closed circuit position. The steam valve 98 is controlled, among other things, by a pressure responsive switching mechanism 104, a low temperature responsive switching mechanism 105 and a high temperature responsive mechanism 106.

25 The steam pressure responsive switching mechanism 104 comprises a bellows 107 which communicates with the steam pipe 97 between the steam pipe 15 and the steam valve 98. The bellows 107 operates a switch carrier 108 that supports a mercury switch 109 having high and low pressure contacts. This pressure responsive mechanism may also take the general form shown in the above mentioned Phelan patent and is 30 preferably adjusted so that the high pressure contacts close at about 13 lbs. steam pressure and the low pressure contacts close at approximately 10 lbs. steam pressure.

35 The low temperature responsive switching mechanism 105 comprises a bellows 110 which communicates with a temperature responsive bulb 111 by means of a capillary tube 112. The bellows 110, tube 112 and capsule 111 are charged with a suitable amount of a proper fluid as is well-known in the art. The bellows 110 operates 40 a switch support 113 which carries a mercury switch 114. This switch 114 is provided with a pair of low temperature contacts that close at some minimum safe temperature of say, 40° F. and the high temperature contacts thereof close 45 at a temperature value slightly above this. The high temperature responsive switching mechanism 106 is similar to the low temperature responsive switching mechanism 105 and comprises a bellows 120 which is connected to a capsule 121 by means of a capillary tube 122. This bellows 120 operates a switch support 123 which in turn carries a mercury switch 124. The mercury switch 124 is provided with a pair of normally 50 open high temperature contacts that are closed upon an excessive temperature of say 100° F. The mercury switch 124 is also provided with a pair of low temperature contacts, which are normally closed and remain closed for all values 55 below 100° F.

60 The condensate formed in steam jet injector 61 flows to a condenser 130 from which it is removed by an ordinary electrically operated condensate or vacuum pump 131 which returns the condensate to the boiler 14 by means of a pipe 65 132 and also eliminates the air. The vacuum pump 131 is controlled by a relay 133 which comprises a relay coil 134 that operates an armature 135. Armature 135 controls a switch arm 136 which is adapted to engage a cooperating

70 contact 137. A vacuum responsive switching mechanism 138 comprises a bellows 139 that communicates with the interior of condenser 130. This bellows controls a switch carrier 140 which in turn supports a mercury switch 141. The arrangement is such that mercury switch 141 only closes when the vacuum in condenser 130 is at or below about 26 inches of mercury.

75 The condenser 130 is cooled by water passing through a coil 142. This water is pumped to a spray 143 by means of a spray pump 144. The water which leaves the spray 143 drops down through a cooling tower 145 and is collected at the bottom and returned to the condenser cooling coil 142 by a pipe 146. In order to increase the 80 cooling effect of the cooling tower, it is preferably supplied with an electrically operated blower 147. Cooling tower spray pump 144 is controlled by a relay 148 which comprises a relay coil 149, an armature 150, a switch arm 151 and a cooperating contact 152. The cooling tower blower 147 is controlled by a relay 153 which comprises a relay coil 154, an armature 155, a switch arm 156, and a cooperating contact 157.

85 The control system for these various devices also includes a second summer-winter switch having three switch arms 160, 161 and 162. This summer-winter switch, which is generally indicated at 163 is shown in its winter position where-in switch arm 160 engages a contact 164 and 90 switch arm 162 engages a contact 165, it being noted that switch arm 161 does not engage any contact whatsoever when in the winter position. It will also be noted that the switch arm 161 is 95 permanently connected to contact 164 by a wire 166. When the summer-winter switching mechanism 163 is thrown to the summer position, switch arm 160 engages a contact 167, switch arm 161 engages a contact 168 and switch arm 162 100 engages a contact 169.

105 Turning now to Fig. 2, the damper 92 is secured to a shaft 175 which is journalled in the outdoor air inlet duct 90. A pulley 176 is secured to one extremity of shaft 175. Similarly, the damper 93, which is located in return air inlet duct 91, is 110 carried by a shaft 177 that is journalled in the sides of return air duct 91. A pulley 188 is secured to the extremity of shaft 177. An inlet damper actuating mechanism generally indicated at 189 includes a vertically movable actuating rod 190 which operates an arm 191 pivoted at 192. A cable 193 has one of its ends secured to arm 191 and is then threaded over pulleys 176 and 188 and has its opposite end secured to a weight 194. It will therefore be evident that when the right 115 hand end of member 191 is moved upwardly, the pulley 176 will rotate in a clockwise direction to further close off the outdoor inlet duct 90 and the pulley 188 will be rotated in a counter-clockwise direction to more widely open return air inlet duct 91. Upon downward movement of member 191, the reverse action takes place. The 120 dampers 92 and 93, therefore, together with their controlling pulleys and cable comprise a mixing damper. When arm 191 moves to its extreme upper position, outdoor air inlet duct 90 will be 125 completely closed off and return air inlet duct 91 will be completely opened. Similarly, when arm 191 moves to its intermediate position, outdoor air inlet duct 90 will be completely opened and return air inlet duct 91 will be completely closed off, the dampers 92 and 93 having moved through 90 angular degrees. When arm 191 moves to its lowermost position, outdoor air in- 130

let duct 90 will again be completely closed off and return air duct will be completely opened, the dampers having moved through 180 angular degrees. Provision is made whereby arm 191 only 5 moves through the upper half of its range when the system is operating on its winter cycle but moves through its complete range when the system is operating on its summer cycle.

The lower end of actuating rod 190 is provided 10 with teeth indicated at 195. These teeth cooperate with a pinion 196, carried by a shaft 197. Shaft 197 further carries a pair of gears 198 and 199. Gear 198 cooperates with a pinion 200 secured to the rotor shaft 201 of a motor 202 which 15 comprises a rotor 203 and a field winding 204. The gear 199 cooperates with a pinion 205 secured to the rotor shaft 206 of a motor 207 which includes a rotor 208 and a field winding 209. Shaft 197 further carries a pair of limit switch operators 210 and 211. Limit switch operator 210 is 20 adapted to operate a limit switch 212, whereas limit switch operator 211 is adapted to operate a limit switch 213. The shaft 197 further operates a balancing contact arm 214 which is adapted 25 to sweep across a balancing resistance 215. The arrangement is such that balancing contact arm 214 moves from the extreme left hand end of balancing resistance 215 to the extreme right hand end thereof while arm 191 moves from its 30 lowermost position to its highest position.

The field windings 204 and 209 of motors 202 and 207 are adapted to be controlled by a balanced relay mechanism which includes a switch arm 216. Upon movement of switch arm 216 in 35 one direction, it is adapted to engage a contact 217 and upon movement in the other direction it is adapted to engage a contact 218. Switch arm 216 is controlled by a plunger 219 to which it is connected by a connecting means 220. Plunger 219, in turn, is controlled by a pair of similar 40 solenoids 221 and 222.

The two solenoids 221 and 222 are adapted to be selectively controlled by a pair of potentiometer thermostats 223 and 224. The potentiometer 45 thermostat 223 is the winter thermostat and responds to outdoor temperature. It comprises a bimetallic actuator 225 which moves a contact arm 226 across a resistance 227 upon changes in outside temperature. The range of this winter 50 outdoor thermostat is preferably such that it moves from the extreme left hand end of resistance 227 to its extreme right hand end when the outdoor temperature decreases from approximately 65° F. to 20° F. The resistance 227 is wound uniformly so that equal changes in resistance are effected by equal movements of contact arm 226. The summer outdoor thermostat 224 comprises a bimetallic actuator 228 that controls 55 a contact arm 229. This contact arm 229 is adapted to sweep across a resistance 230 which is wound unevenly or in a tapered fashion. The range of this instrument is preferably such that the contact arm 229 moves from the extreme left hand end of resistance 230 to its extreme right 60 hand end when the outdoor temperature falls from approximately 80° F. to 65° F. The winding of resistance 230 is tapered in such manner that contact arm 229 engages the electrical center of resistance 230 when the outdoor temperature is 65 approximately 70° F. Under such conditions, the contact arm 229 is in the position shown. The summer and winter outdoor thermostats 224 and 223 are selectively placed in control of the damper 70 operating mechanism 189 by means of a summer-winter switch 231. This switch comprises a pair 75

of switch arms 232 and 233 which engage contacts 234 and 235 when in the winter position shown in Fig. 2 and engage contacts 236 and 237 when in the summer position.

Two adjusting rheostats, the utility of which 5 will be hereinafter brought out, are indicated at 238 and 239. The rheostat 239 is shown as being in such position that practically all of its resistance is in circuit with the outdoor winter resistance 227. With the rheostat 239 adjusted as 10 shown, its resistance is equal to the resistance of outdoor winter rheostat 227. The combined resistance of outdoor winter resistance 227 and the operative resistance of rheostat 239 is equal to the outdoor summer resistance 230 and is also 15 equal to the balancing resistance 215. With the rheostat 238 adjusted as shown, none of its resistance is in circuit with the outdoor winter resistance 227.

Power is supplied to damper control mechanism 189 and its associated control devices and 20 circuits by means of the low voltage secondary 240 of a step-down transformer 241, having a high voltage primary 242 connected to suitable line wires. One side of secondary 240 is connected to one end of field winding 204 through 25 limit switch 212 by means of wires 243 and 244, while the other side of secondary 240 is connected to one end of field winding 209 through limit switch 213 by means of wires 245 and 246. 30 The other ends of field windings 204 and 209 are connected to relay switch arm 216 by means of wires 247, 248 and 249.

The adjacent ends of solenoids 221 and 222 are 35 interconnected, their junction being indicated at 250. The opposite or free end of solenoid 221 is connected to one side of secondary 240 by means of wires 243 and 251. This end of solenoid 221 is also connected to the left hand end of balancing 40 resistance 215 and to rheostat 238, through a protective resistance 252, by means of wires 253, 254 and 255. The free end of solenoid 222 is connected to one side of secondary 240 by wires 245 and 256. This same end of solenoid 222 is also connected to the right hand end of balancing 45 resistance 215 and to switch arm 233 through a protective resistance 257, by wires 258, 259 and 260. Contact 235 of summer-winter switch 231 is connected to rheostat 239 by a wire 261. It will therefore be noted that with summer-winter 50 switch 231 in the winter position shown, the outdoor winter resistance 227 and its series connected rheostats 238 and 239 are in parallel with balancing resistance 215 and solenoids 221 and 222 in series, all of which are connected across the 55 secondary 240 of transformer 241, it being noted that protective resistances 252 and 257 are inserted between certain portions of these parallel circuits. The junction 250 of solenoids 221 and 222 is connected to balancing contact arm 214 60 and to switch arm 232 of summer-winter switch 231 by wires 262, 263 and 264. Contact 234 of summer-winter switch 231 is connected to thermostatic element 225 by a wire 265. When summer-winter switch 231 is thrown to its summer 65 position, the right hand end of outdoor summer-resistance 230 is connected to wire 260 by reason of a wire 266. The thermostatic element 228 is connected to wire 264 under these conditions by a wire 267. The left hand end of outdoor summer resistance 230 is permanently connected to the rheostat 238 by means of a wire 268. A small number of turns of solenoid 221 is connected to contact 218 by a wire 269 and a small number 70 75

of turns of solenoid 222 is connected to contact 217 by a wire 270.

Winter operation of inlet air dampers 92 and 93

With the parts in the position shown, the outdoor temperature is approximately 42° F. as indicated by the fact that contact arm 226 is engaged with outdoor winter resistance 227 substantially at its center. The balancing contact arm 214 is therefore engaging balancing resistance 215 midway between its center and its right hand end. As a result, solenoids 221 and 222 are equally energized and plunger 219 is in its mid-position wherein relay switch arm 216 is disengaged from both contacts 217 and 218. Field windings 204 and 209 are therefore connected in series across the secondary 240 of transformer 241 by a circuit as follows: secondary 240, wire 243, wire 244, limit switch 212, field winding 204, wire 241, wire 248, field winding 209, limit switch 213, wire 246 and wire 245 to the other side of secondary 240. The motors 202 and 207 are equally energized. These motors are arranged so that they buck one another and, since they are equally energized with the parts in the position shown, their torques will be balanced and the shaft 197 will be stationary. Dampers 92 and 93 are therefore in the position shown wherein equal amounts of outdoor air and return air are passed through air conditioning chamber 11.

If the outdoor temperature should fall somewhat, contact arm 226 will move along resistance 227 towards the right hand end thereof. Such movement will unbalance the energizations of solenoids 221 and 222 so that solenoid 222 becomes more highly energized than solenoid 221. Plunger 219 therefore moves to the right and brings relay switch arm 216 into engagement with contact 217. This causes the small number of turns of solenoid 222 to be placed in parallel with field winding 209 and the total flow of current through this small number of turns of solenoid 222 and through field winding 209 will traverse field winding 204 by a circuit as follows: secondary 240 of transformer 241, wire 243, wire 244, limit switch 212, field winding 204 and wire 247 at which point the circuit branches, one portion going by way of wire 248, field winding 209, limit switch 213 and wire 246 to wire 245 and the other side of secondary 240, whereas the other part goes by way of wire 249, relay switch arm 216, contact 217, wire 270, the small number of turns of solenoid 222 and wire 256 to wire 245 and the same side of secondary 240. The current flow through the small number of turns of solenoid 222 provides an additional pull on plunger 219 towards the right so that relay switch arm 216 more firmly engages contact 217 and eliminates all possibility of chattering between the relay switch arm 216 and contact 217. Motor 202 is now more highly energized than motor 207 wherefore its torque will be greater, permitting motor 202 to drive motor 207 backwards. Rotor 203 of motor 202 rotates in a counter-clockwise direction as viewed from the left and therefore rotates shaft 197 clockwise when viewed from the same direction. Balancing contact arm 214 will therefore travel along balancing resistance 215 towards the right hand end thereof. This movement of balancing contact arm 214 along balancing resistance 215 will gradually rebalance the energizations of solenoids 221 and 222. When the pull of solenoid 221 has thus been made

equal to the combined pull of solenoid 222 and the extra energization of its small number of turns, plunger 219 will be returned to its intermediate position and move switch arm 216 from engagement with contact 217. The initial separation will be very slight, but when it has occurred the circuit through the small number of turns of solenoid 222 will be interrupted whereupon the plunger 219 will move to the left a little further and relay switch arm 216 will again be well spaced from both contact 217 and 218. Separation of relay switch arm 216 from contact 217 again establishes the series circuit through field windings 204 and 209 whereupon motors 202 and 207 will again be equally energized and further upward movement of shaft 197 will cease. Actuating rod 190 has been moved upwardly a small amount during the time that balancing contact arm 214 traveled along balancing resistance 215 and this upward movement moves arm 191 closer to its upper limit allowing weight 194 to move downwardly a small amount whereby pulley 176 is rotated in a clockwise direction and pulley 188 is rotated in a counter-clockwise direction. Outdoor inlet damper 92 is therefore moved towards a vertical position and partially closes off the outdoor inlet duct 90 whereas return air damper 93 is moved towards horizontal position and opens return air duct 91 more widely. In this manner, if the outdoor temperature falls, the outdoor air inlet duct 90 is gradually closed off and when contact arm 226 finally engages the extreme right hand end of outdoor winter resistance 227, the outdoor inlet duct 90 will be completely closed off and the return air duct 91 will be completely opened.

It may be desirable to take in a small amount of outside air through outdoor inlet duct 90 at all times irrespective of how low the outdoor temperature becomes. If this action is desired, rheostat 238 may be moved from its inoperative position shown in Fig. 2 of the drawings to a position wherein a small amount of its resistance is connected in circuit with outdoor winter resistance 227. This position of rheostat 238 is illustrated in dotted lines. When this is done, there will always be a small amount of resistance between wire 255 and contact finger 226 even though the contact finger 226 engages the extreme right hand end of outdoor winter resistance 227. As a result, balancing contact arm 214 will never move to the extreme right hand end of balancing resistance 215 in order to balance the energizations of solenoids 221 and 222. Arm 191 will therefore never be moved to its extreme upper limit and outdoor air damper 92 will never move to its full vertical position. In this manner, a variable amount of outdoor air, depending upon the adjustment of rheostat 238, will be allowed to flow to air conditioning chamber 11 irrespective of how low the outdoor temperature falls.

Whenever the outdoor temperature rises, contact arm 226 will move along outdoor winter resistance 227 towards the left hand end thereof. Such movement unbalances the energization of solenoids 221 and 222 in such manner that solenoid 221 will become the more highly energized. This causes movement of plunger 219 towards the left, whereupon relay switch arm 216 is moved into engagement with contact 218. Field winding 204 and a small number of turns of solenoid 221 will therefore be placed in parallel and the full current flow through field winding 204 and the small number of turns of solenoid 221

will flow through field winding 209. This circuit is as follows: secondary 240 of transformer 241, wire 245, wire 246, limit switch 213, field winding 209, and wire 248 at which point the circuit branches, one part going by way of wire 247, field winding 204, limit switch 212 and wire 244 to wire 243 and the other side of secondary 240, whereas the other part goes by way of wire 249, relay switch arm 216, contact 218, wire 269, the small number of turns of solenoid 221 and wire 251 to wire 254 and the same side of secondary 240. Motor 207 is therefore more highly energized than motor 202 and drives motor 202 backwards. Rotor 208 of motor 207, when thus energized, rotates in a clockwise direction as viewed from the left and therefore rotates shaft 197 counter-clockwise as viewed from the same direction. Balancing contact arm 214 therefore travels along balancing resistance 215 towards the left hand end thereof until the energizations of solenoids 221 and 222 are rebalanced in the manner heretofore described for a decrease in outdoor temperature. Arm 191 is therefore moved downwardly a small amount whereupon outdoor air inlet damper 92 is moved towards its horizontal position and return air inlet damper 93 is moved towards its vertical position. If the outdoor temperature rises to 65° F. or higher, contact arm 226 will engage the extreme left hand portion of outdoor resistance 227. Balancing contact finger 214, under these conditions, will only move to the mid-portion of balancing resistance 215 in order to rebalance the energizations of solenoids 221 and 222. This is true because the external resistance in circuit with outdoor winter resistance 227 by reason of the adjustment of rheostat 239 is equal to the resistance 227 as heretofore explained, whereas the balancing resistance 215 is equal to the combination of rheostat 239 and outdoor winter resistance 227. Outdoor winter thermostat 233 is therefore only capable of moving arm 191 to its intermediate position wherein outdoor inlet damper 92 assumes a horizontal position and return air damper 93 is moved to its vertical position.

If it should be desired to recirculate a small amount of air even though the outdoor temperature is at or above 65° F., this can be accomplished in a manner similar to the manner in which a small amount of outdoor air can always be admitted irrespective of how low the outdoor temperature becomes by adjusting rheostat 239 to some position such as the dotted position shown in Fig. 2 wherein a little more resistance is placed in circuit with outdoor winter resistance 227. If this is done, the resistance of rheostat 239 becomes somewhat greater than the resistance of outdoor winter resistance 227 so that the outdoor winter thermostat 233 will be incapable of moving outdoor air damper 92 to its full horizontal position and return air inlet damper 93 to its full vertical position.

From the foregoing description of the winter operation of the mixing damper comprised by outdoor air damper 92 and return air damper 93, it will be seen that the amount of outdoor and return air circulated through air conditioning chamber 11 is gradually varied upon changes in outdoor temperature ranging from 20° F. to 65° F. At 20° F., all return air is circulated and no outdoor air is circulated, whereas at 65° F. all outdoor air and no return air is circulated. For all intermediate temperatures, a proportionate amount of outdoor and return air is circu-

lated. Also by proper adjustment of rheostats 238 and 239, the apparatus can be arranged so that some outdoor air will always be circulated irrespective of how low the outdoor temperature becomes and/or a small amount of return air can always be circulated irrespective of how high the outdoor temperature becomes.

The arm 191 carries a mercury switch 275 having two pairs of contacts 276 and 277. The contacts 276 are closed whenever the arm 191 is above its horizontal position and are opened when the arm 191 moves to its horizontal position at which time contacts 277 are closed. The contacts 276 are connected to steam valve 9 by wires 278 and 279, whereas contacts 277 are connected to steam valve 9 by wires 279 and 280. When contacts 276 are closed, the steam valve 9 is opened and when contacts 277 are closed, the steam valve 9 is closed. Power is furnished to steam valve 9 by suitable line wires indicated at 281. Such valves and their control are well-known in the art and no further explanation is thought to be necessary at this time. It being remembered that arm 191 only reaches horizontal position during winter operation when the outdoor temperature is at or above 65° F., it will be seen that steam valve 9 is always opened to permit flow of steam to preheat coil 12 whenever the outdoor temperature is below 65° F. but if the outdoor temperature should rise to 65° F. or higher, the contacts 277 will be closed and the steam valve 9 will close so that no steam can flow to preheat coil 12. The exact position of arm 191 at which steam valve 9 will be opened or closed can be varied by varying the position of mercury switch 275 in respect to the arm 191.

Summer operation of inlet air dampers 92 and 93

For summer operation of the inlet air dampers 92 and 93, the summer-winter switch 234 is thrown to its position opposite that in which it is shown in the drawings so that switch arm 232 is brought into engagement with contact 236 and switch arm 233 is brought into engagement with contact 237. The left hand end or the hot end of outdoor summer resistance 230 will therefore be connected to the left hand end of balancing resistance 215 through the rheostat 238 which, in the position shown, does not insert any external resistance in series with outdoor summer thermostat 230. It will be noted that this connection is opposite to the winter connection in that in the winter time, the cold end of outdoor winter resistance 227 is connected to the right hand end of balancing resistance 215. The right hand end or cold end of outdoor summer resistance 230 is connected to the right hand end of balancing resistance 215. With the parts in the position shown, the contact arm 229 of outdoor summer thermostat 244 is contacting the electrical center of outdoor summer resistance 230. It being remembered that this outdoor summer resistance 230 is equal to the balancing resistance 215, solenoid 221 will be more highly energized than solenoid 222 since balancing contact arm 214 is engaged with the balancing resistance 215 at a point midway between its center and its right hand end. Plunger 219 will therefore move to the left and bring switch arm 216 into engagement with contact 218 whereupon motor 207 will become more highly energized than motor 202 as heretofore explained and balancing contact arm 214 will thereby be moved along balancing resistance 215 toward the left hand end thereof. When balancing contact arm 214 moves to approximately the middle of balancing resist-

ance 215, the energizations of solenoids 221 and 222 will again be balanced whereupon further movement of shaft 197 will cease. During this operation, arm 191 is moving downwardly to its mid position with the result that outdoor damper 92 is moved to horizontal position and return damper 93 is moved to its vertical position.

These positions of the parts represent a comfortable outdoor temperature of 70° F., wherein all of the air passing through air conditioning chamber 11 is taken from the outdoors. If the outdoor temperature should fall, it will be apparent that the taking of a large amount of this cooler outdoor air might result in making the building too cold. Such a fall in outdoor temperature is accompanied by movement of contact arm 229 along outdoor summer resistance 230 towards the right hand end thereof. This will cause solenoid 221 to become more highly energized than solenoid 222, whereupon arm 191 will be moved downwardly. Outdoor damper 92 will therefore be rotated in a counter-clockwise direction towards its vertical position and return air damper 93 will be rotated in a clockwise direction towards its horizontal position. In this manner, if the outdoor temperature decreases in the summer from an intermediate temperature of 70° F. the amount of outdoor air taken into the air conditioning chamber 11 will be gradually reduced until no outdoor air whatsoever is taken therein when the outdoor temperature falls to 65° F. At the same time, the amount of return air is increased from zero to its full flow. When the outdoor temperature rises so that contact arm 229 moves along outdoor summer resistance 230 towards its left hand end, solenoid 222 is more highly energized than solenoid 221 which results in upward movement of arm 191. This causes clockwise movement of outdoor air damper 92 and counter-clockwise movement of return air damper 93. Therefore, whenever the outdoor temperature rises above 70° F., the amount of outdoor air taken into air conditioning chamber 11 will be gradually decreased and when the outdoor temperature reaches 80° F., no outdoor air whatsoever will be allowed to pass through air conditioning chamber 11 but all return air will be circulated therethrough.

In this manner, in the summer when the outdoor temperature is approximately that desired within the building, no air will be recirculated and all of the air supplied to the building will be fresh outdoor air. However, if the outdoor temperature rises or falls below that desired within the building, the amount of outdoor air taken into the building will be decreased. At some undesirable low temperature such as 65° F. and at some undesirable high temperature such as 80° F. all return air will be circulated and there will be no outdoor air or fresh air taken into the building.

As in the winter time, it may be desirable to take in some fresh air irrespective of how high the outdoor temperature becomes. This can be accomplished by again moving rheostat 238 to its dotted position. When this is done, it will be impossible for the outdoor summer thermostat 224 to completely close off the outdoor air inlet duct upon rise in outdoor temperature in the same manner that the outdoor winter thermostat is incapable of completely closing off the outdoor inlet duct upon a fall in outdoor temperature when the rheostat 238 is adjusted in this same manner.

It should be noted that by means of the use

of external resistance in the form of rheostat 238 during the winter operation, the inlet dampers 92 and 93 are restricted to a 90 angular degree movement which in this particular embodiment of the invention means that the outdoor air supplied may be varied from zero to a maximum upon outdoor temperature change in a single direction. However, in the summer, by the elimination of this external resistance, the inlet dampers 92 and 93 are permitted to move through 180 angular degrees which means in this embodiment of the invention that the outdoor air may be varied from a minimum at low outdoor temperature to a maximum at a desired outdoor temperature and continue on to a minimum at high outdoor temperatures all as a result of temperature change in one direction. It is to be noted particularly that the transition from 90 angular degree operation in the summer to 180 angular degree operation in the winter is accomplished entirely by the insertion of or the exclusion of the proper resistance which having once been determined need never be changed. The change-over from summer operation to winter operation requires only the operation of a reversing switch and no change in linkage between the dampers and the controlling mechanism 189 or any other changes are necessary.

The outlet mixing damper 96 is carried by a shaft 285 to which is secured a pulley 286. This mixing damper 96 is controlled by a mechanism generally indicated at 287 which mechanically is a duplicate of the mechanism 189. The outlet damper mechanism 287 comprises a vertical movable actuator 288 which operates an arm 289, pivoted at 290. The lower end of actuating rod 288 is provided with teeth 291 which are engaged by a pinion 292 carried by a shaft 293. Shaft 293 further carries a pair of gears 294 and 295. Gear 294 meshes with a pinion 296 secured to the rotor shaft 297 of a motor 298. Motor 298 comprises a rotor 299 and a field winding 300. Similarly, gear 295 meshes with a pinion 301 secured to the rotor shaft 302 of a motor 303. Motor 303 includes a rotor 304 and a field winding 305. Shaft 293 also carries a pair of limit switch operators 306 and 307. Limit switch operator 306 is adapted to operate a limit switch 308 while limit switch operator 307 is adapted to operate a limit switch 309. Shaft 297 also carries a balancing contact arm 310 which is adapted to sweep back and forth across a balancing resistance 311.

The mechanism 287 is adapted to be controlled herein by a potentiometer thermostat 312 or by a manually operable potentiometer 313. The potentiometer thermostat 312 comprises a bimetallic actuator 314 that operates a contact arm 315 which sweeps back and forth across a control resistance 316 upon changes in the temperature to which thermostatic element 314 responds. In the particular embodiment of the invention herein shown, the thermostat 312 responds to changes in basement air and contact arm 315 engages the extreme right hand end of resistance 316 when the basement temperature is approximately 68° F. and engages the extreme left hand end of resistance 316 when the basement temperature rises to approximately 70° F.

This resistance 316 is connected in parallel with balancing resistance 311 through a summer-winter reversing switch generally indicated at 318 by means of which the relation of resistance 316 to balancing resistance 311 may be reversed. The summer-winter switch 318 com-

prises a pair of switch arms 319 and 320 which engage contacts 321 and 322 when the summer-winter switch 318 is in winter position. When the summer-winter switch 318 is thrown to its summer position switch arm 319 engages contact 323 and switch arm 320 engages a contact 324. Contact 321 is connected to contact 324 by a wire 325 and contact 322 is connected to contact 323 by a wire 326.

10 The manual rheostat 313 comprises a resistance 327 and a manually operable contact arm 328. The resistances 316 and 327 control a pair of solenoids 329 and 330 having their adjacent ends interconnected, this junction being indicated at 15 331. These solenoids 329 and 330 control the position of a plunger 332 that is connected to a relay switch arm 333 through connecting means 334. Switch arm 333 is adapted to selectively engage a pair of contacts 335 and 336. The controls 20 for mechanism 287 also include a manually operable switch that includes a switch arm 337 adapted to engage a contact 338 or a contact 339 which is connected to the contact arm 328 of manual rheostat 313.

25 Power is supplied by a step-down transformer 340 having a low voltage secondary 341 and a high voltage primary 342 that is connected to suitable line wires. One end of field winding 300 is connected to secondary 341 through limit switch 308 by wires 343 and 344. One end of field winding 305 is connected to the other side of secondary 341 through limit switch 309 by wires 345 and 346. The other ends of field windings 300 and 305 are connected to relay switch arm 333 by wires 347, 348 and 349. The solenoids 329 and 330, in series, are connected across secondary 341 by wires 343, 350, 351 and 345. Balancing resistance 311 is connected in parallel with solenoids 329 and 330, in series, through protective resistances 352 and 353 by wires 354, 355, 356 and 357. The left hand end of balancing resistance 311 is connected to switch arm 320 and to the left end of manual resistance 327 by wires 358, 359 and 360. The right hand end of balancing resistance 311 is connected to switch arm 319 and the right hand end of manual resistance 327 by wires 361 and 362. The left hand end of control resistance 316 is connected to contact 324 by a wire 363 and the right hand end thereof is connected to contact 323 by a wire 364. The junction 331 of solenoids 329 and 330, balancing contact arm 310 and manual switch arm 337 are interconnected by wires 365 and 366. Contact 338 is connected to thermal element 314 by a wire 367. A small number of turns of solenoid 329 is connected to contact 336 by a wire 368 and a small number of turns of solenoid 330 is connected to contact 335 by a wire 369.

60 A cable 370 is threaded over pulley 286 and has one of its ends connected to arm 289, whereas its other end is connected to a weight 371.

Operation of outlet air mixing damper 96

The parts are shown in their winter position 65 wherein switch arms 319 and 320 of summer-winter switch 318 are in engagement with contacts 321 and 322. The right hand end of control resistance 316 is therefore connected to the left hand end of balancing resistance 311 and the 70 left hand end of control resistance 316 is connected to the right hand end of balancing resistance 311. The manual switch 337 is engaged with contact 338 whereby contact arm 315 is connected to balancing contact finger 310 and junction 331. The thermostat 312 is therefore in

control of the damper operating mechanism 287. The basement temperature is intermediate or about 69° F. since contact arm 315 is engaged with the middle portion of basement resistance 316. This basement resistance 316 and the manual resistance 327 and the balancing resistance 311 all have the same value and all are uniformly wound. Therefore, balancing contact finger 310 is engaged with the mid-portion of balancing resistance 311 and the arm 289 is intermediate 5 its limits of movement. The damper 96 is in its mid-position allowing equal flows of air through room duct 94 and basement duct 95. It will be noted that damper 96 can only move through 90° and since arm 289 has the same range of movement as arm 191, and since the cables 370 and 193 are connected to arms 289 and 191 the same distance from the pivotal points 290 and 192, the pulley 286 must be twice as large as the pulleys 176 and 188 in order that damper 96 will only 10 move through this 90 angular degrees for the complete movement of arm 289.

Now if the basement temperature should fall, contact arm 315 will move along basement resistance 316 towards the right hand end thereof. 15 This will cause solenoid 330 to become more highly energized than solenoid 329 whereupon plunger 332 moves to the right and relay switch arm 333 engages contact 335. Field winding 305 and the small number of turns of solenoid 330 in parallel 20 are thereby placed in series with field winding 300 by the following circuit: secondary 341 of transformer 340, wire 343, wire 344, limit switch 308, field winding 300 and wire 347 at which point the circuit branches, one part going by way of wire 348, field winding 305, limit switch 309, wire 346, and wire 345 to the other side of secondary 341, whereas the other part goes by way of wire 349, relay switch arm 333, contact 335, wire 369, the small number of turns of solenoid 330, wire 351 and wire 345 to the same side of secondary 341. 25 Motor 298 is thereby energized more highly than motor 303 and its rotor 299, which rotates in a counter-clockwise direction as viewed from the left, causes shaft 293 to rotate in a clockwise direction. Balancing contact arm 310 therefore 30 moves along balancing resistance 211 towards the right hand end thereof until the energizations of solenoid 329 and 330 are rebalanced as previously explained in connection with the mechanism 189. 35 This movement causes upward movement of actuating rod 288 and arm 289 whereupon mixing damper 96 is rotated in a clockwise direction to cause a larger delivery of air through the basement outlet duct 95. In the event the basement temperature should fall to 68° F. so 40 that contact arm 315 engages the extreme right hand end of basement resistance 316, the arm 289 will be moved to its upper limit of movement and mixing damper 96 will completely close off 45 room outlet duct 94 whereby all of the air from air conditioning chamber 11 will be delivered 50 through the basement duct 95.

Whenever there is a rise in basement temperature, contact arm 315 will move along basement 55 resistance 316 towards the left hand end thereof whereby solenoid 329 will be more highly energized than solenoid 330. Plunger 332 will therefore move to the left and bring relay switch arm 333 into engagement with contact 336. This 60 places a small number of turns of solenoid 329 in parallel with field winding 300, the full current flow traversing field winding 305 by a circuit as follows: secondary 341 of transformer 340, wire 345, wire 346, limit switch 309, field 65

winding 305 and wire 348 at which point the circuit branches, one point going through wire 347, field winding 300, limit switch 308, and wire 344 to wire 343 and the other side of secondary 341 while the other part goes by way of wire 349, switch arm 333, contact 336, wire 368, a small number of turns of solenoid 329 and wire 350 to wire 343 and the same side of secondary 341. Motor 303 is therefore more highly energized than motor 298 and its rotor rotates in a clockwise direction as viewed from the left. Shaft 293 is thereby rotated in a counter-clockwise direction and balancing contact arm 310 moves along balancing resistance 311 towards the left hand end thereof. This movement continues until the energizations of solenoid windings 329 and 330 have been rebalanced in a manner heretofore set forth. Such movement of shaft 293 is accompanied by downward movement of actuating rod 288 and arm 289 whereby damper 96 is rotated in a counter-clockwise direction to diminish the flow of air through basement outlet duct 95 and to increase the flow through room outlet duct 94. If the basement temperature increases to 70° F., contact arm 315 will engage the extreme left hand end of basement resistance 316 in order to rebalance the solenoids 329 and 330. Balancing contact finger 310 will therefore move to the extreme left-hand end of balancing resistance 311 and arm 289 moves to its lowermost position rotating damper 96 in a counter-clockwise direction until it is horizontal and completely shuts off all flow of air through basement outlet duct 95.

In this manner, if the basement temperature varies from 68° F. to 70° F. in the winter, the flow of air through basement outlet duct 95 is diminished from a maximum to no flow whatsoever. Correspondingly, the flow of air through the room outlet duct 94 is increased from no flow whatsoever to the maximum flow.

When the summer-winter switch 318 is thrown to its summer position wherein switch arm 319 engages contact 323 and switch arm 320 engages contact 324, the right hand end of basement resistance 316 will be connected to the right hand end of balancing resistance 311 and the left hand end of basement resistance 316 will be connected to the left hand end of balancing resistance 311. In other words, movement of summer-winter switch 318 from its winter position to its summer-position reverses the connections of basement resistance 316. As a result, in the summer when the basement temperature varies from its minimum 68° F. to its maximum 70° F. the flow of air through basement outlet duct 95 will be increased from no flow whatsoever to a maximum flow.

Under some conditions, it may be desirable to manually control the mixing damper 96 irrespective of temperature conditions in the basement. Under such conditions, manual switch arm 331 is moved from engagement with contact 338 and into engagement with contact 339. This disconnects contact arm 315 from balancing contact arm 310 and junction 331 and connects manual contact arm 328 therewith. The manual rheostat 313 is therefore placed in control and the mixing damper 96 may be moved to the desired position by manual manipulation of contact arm 328 irrespective of the prevailing basement temperature.

In both the mechanisms 189 and 287, the limit switches and actuators are provided in order that the movement of arms 191 and 289 may be limited if desired. Such limit switches of an ad-

justable nature are well-known in the art and their utility herein will be appreciated without further explanation.

The protective resistances outlined in both of these systems prevent a complete short-circuiting of the solenoid coils when the controlling contact arms move to an extreme position so as to result in movement of the balancing contact arms in the opposite extreme position.

For a more complete understanding of modulating systems of this general nature, reference may be had if desired to the copending application of Lewis L. Cunningham, Serial No. 673,236 which was filed May 24, 1933.

Winter operation of the complete system 15

Returning now to Fig. 1 of the drawings, the parts are shown in their winter operating position and operating on the day cycle. The room or space temperature is at or above the desired minimum since contacts 23 of room thermostat 23 are open. The boiler pressure is below the permissible maximum since low pressure contacts 52 of mercury switch 51 are closed. The pilot 20 is operating properly and bimetallic element 58 25 is in engagement with contact 59. The boiler water level is sufficiently high as indicated by low water cut-off switch 57 being in closed position. Gas valve 18 is closed so no fuel is being supplied to main burner 17, and valve 16 is open. 30

Power is supplied to certain parts of the system by a hot line 375 and a ground line 376. The winding 79 of the timer motor is constantly energized by a circuit as follows: hot line 375, wire 377, wire 378, and timer motor winding 79 to ground. 35 Timer switch 82 is in closed position since the system is operating on the day cycle. Relay coil 73 of relay 72 is therefore energized as follows: hot line 375, wire 377, wire 380, wire 381, timer switch 82, wire 382, wire 383 and relay coil 40 73 to ground. Switch arm 73 is therefore engaged with contact 76 whereby blower 71 is energized as follows: line 384, switch arm 75, contact 76, wire 385, wire 386, blower 71, wire 387, and line 388. Air is therefore being drawn into 45 air conditioning chamber 11 through outdoor air inlet duct 90 and return air inlet duct 91 in proportions determined by the settings of dampers 92 and 93 which settings are controlled by the outdoor winter thermostat 223 in the manner heretofore explained in detail. This air passes over preheat coil 12, water spray 86, refrigerating coil 60, reheat coil 13, and is delivered to the rooms and basement in proportions determined by the setting of damper 96, the setting 50 of which is determined by basement thermostat 312 or manual rheostat 313 in the manner heretofore described in detail. The refrigerating coil 60 of course is inoperative in the winter as will become apparent when the summer operation is 55 described. Engagement of switch arm 75 with contact 76 of relay 72 conditions water valve 88 which is controlled by the humidostat 89 for operation. Whenever the relative humidity becomes too low, water valve 88 will be energized as follows: line 384, switch arm 75, contact 76, wire 385, wire 389, water valve 88, wire 390, humidostat 89, wire 391 and line 388. It will 60 therefore be apparent that whenever air conditioning blower 71 is energized, the water valve 65 88 may be energized under the command of the humidostat 89 so as to allow water to be delivered to water spray 86 whereby the air passing through air conditioning chamber 11 may 70 be humidified.

When the room temperature falls below the desired value, contacts 23 of room thermostat 21 will close and energize relay coil 30 of relay 29 as follows: secondary 37 of transformer 38, wire 392, contacts 23, wire 393, contact 27, switch arm 26, wire 394, relay coil 30, and wire 395 to the other side of secondary 37, it being noted that the primary 39 of transformer 38 is permanently connected to suitable line wires. Energization of relay coil 30 attracts its armature 31 which in turn moves switch arms 32 and 35 into engagement with contacts 34 and 36 and at the same time moves switch arm 32 from engagement with contact 33. Engagement of switch arm 35 with contact 36 energizes primary 56 of transformer 55 as follows: hot line 375, wire 396, contact 164, switch arm 160, wire 397, contact 36, switch arm 35, wire 398, switch arm 162, contact 165, wire 399, wire 400, low water cut off switch 57, wire 401, wire 402, and primary 56 to ground. Engagement of switch arm 32 with contact 34 energizes energizing coil 41 of relay 40 as follows: secondary 54 of transformer 55, wire 403, contact 59, bimetallic element 58, wire 404, wire 405, contact 34, switch arm 32, wire 406, low pressure contacts 52 of high limit switch 51, wire 407, energizing coil 41 of relay 40, wire 408, and wire 409 to the other side of secondary 54. Energization of energizing coil 41 attracts armature 43 which moves switch arms 44 and 45 into engagement with contacts 46 and 47 respectively. Engagement of switch arm 44 with contact 46 establishes a holding circuit for energizing coil 41 which is independent of the low pressure contacts 52 of high limit switch 51 and is also independent of switch arm 32 and contact 34 of relay 29. This holding circuit is as follows: secondary 54, wire 403, contact 59, bimetallic element 58, wire 404, wire 410, switch arm 44, contact 46, energizing coil 41, wire 408, and wire 409 to the other side of secondary 54. Engagement of switch arm 45 with contact 47 energizes gas valve 18 as follows: hot line 375, wire 396, contact 164, switch arm 160, wire 397, contact 36 and switch arm 35 of relay 29, wire 398, switch arm 162, contact 165, wire 399, wire 400, low water cut off switch 57, wire 401, wire 411, contact 47, switch arm 45, wire 412, and gas valve 18 to ground.

Gas valve 18 therefore opens and allows fuel to be delivered to main burner 17. This fuel is ignited by pilot burner 20 and combustion thereof generates steam or increases steam pressure in boiler 14. This steam passes by way of pipe 15 through the open valve 16 to reheat coil 13 and then back to the boiler in the usual manner. Some of this steam will also pass through steam valve 9 to preheat coil 12 and back to the boiler provided the outdoor temperature is such that steam valve 9 is open as previously explained. As a result, the air which is passing through air conditioning chamber 11 will be heated and this heated air will pass to the rooms and to the basement in proportions determined by the setting of mixing damper 96.

In the event the steam pressure becomes excessive, low pressure contacts 52 of high limit switch 51 will be opened and the high pressure contacts 53 thereof will be closed. An energizing circuit for bucking coil 42 of relay 40 is then established as follows: secondary 54, wire 403, contact 59, bimetallic element 58, wire 404, wire 410, switch arm 44, contact 46, wire 407, contacts 53, wire 413, wire 414, bucking coil 42 and wire 409 to the other side of secondary 54. The mag-

netic field established by bucking coil 42 equalizes that established by energizing coil 41 whereupon armature 43 will return by gravity to the position shown in the drawings, whereupon the circuit to gas valve 18 is interrupted at 45-47. After the steam pressure drops a predetermined amount, depending upon the differential setting of high pressure responsive switching mechanism 48, the low pressure contacts 52 of high limit switch 51 will again close. In the event room thermostat 21 is still calling for heat so that switch arm 32 is engaged with contact 34 of relay 29, energizing coil 41 of relay 40 will again be energized by the previously described circuit so as to again energize gas valve 18.

If the pilot 20 should become extinguished at any time, the circuit from secondary 54 of transformer 55 will be interrupted resulting in deenergization of gas valve 18 if it should be energized at that time or prevent energization of gas valve 18 upon a subsequent call for heat. If the water level in the boiler should become too low so as to open low water cut off switch 57, the energizing circuit for the primary 56 of transformer 55 as well as the direct operating circuit for gas valve 18 will be interrupted thereby preventing initial energization or the continued energization of gas valve 18.

After a time, the room temperature will be restored and thermostat 21 will move to the position shown in the drawings interrupting the energizing circuit for relay 29 whereupon switch arm 35 will move from engagement with contact 36 and interrupt the energizing circuit for primary 56 of transformer 55. The gas valve 18 will therefore close and remain closed until a subsequent call for heat.

It will be noted that there is no basement thermostat having a direct control over the gas valve 18. However, when the basement becomes cold, the damper 96 is moved toward vertical position so as to divert more of the air passing through air conditioning chamber 11 to the basement. This allows less air to pass to the rooms with the result that the rooms will become cool or stay cooler longer so that in this manner, the basement thermostat 312 has an indirect control over the gas valve 18.

If a time switch such as switch 82 is used, then when this switch opens the previously described energizing circuit for relay coil 73 of relay 72 is interrupted. The blower 71 therefore ceases operating and the humidostat 89 can no longer energize water valve 88. Now if the room should become cold, the gas valve 18 will be energized in the same manner previously explained. Steam pressure will therefore be produced and when this steam pressure becomes sufficiently high, say 2 lbs., bellows 83 will move mercury switch 85 to closed circuit position 60 whereupon relay coil 73 is energized as follows: hot line 375, wire 377, wire 380, wire 415, mercury switch 85, wire 416, wire 383, and relay coil 73 to ground. When operating on the night cycle therefore, blower 71 is only operated when there is sufficient steam and in general this sufficiency of steam will only be present as a result of a call for heat by the room thermostat 21. During the night cycle whenever the blower 71 is operating then the humidostat 89 is again placed in command of the water valve 88.

Summer operation of the complete system

For summer operation, the manual steam valve 16 located in the steam supply pipe 15 is closed.

and the various summer-winter switches are thrown to their summer position. The air conditioning blower 11 will be operated continuously while the time switch 82 is closed by means of the circuit heretofore described in connection with the summer operation. Likewise, the water valve 88 which controls the flow of water to the water spray 86 will be under the control of humidiostat 89.

If the temperature of the room or space rises above 70° F. room thermostat 21 will move to its hot position as shown in Fig. 1 of the drawings, wherein its contacts 24 are closed. If the outdoor temperature is also at or above 70° F. the thermostat 22 will be closed so there will be an energizing circuit for relay coil 30 of relay 29 which is as follows: secondary 37 of transformer 38, wire 392, contacts 24 of thermostat 21, wire 425, contacts 25 of outdoor thermostat 22, wire 426, contact 28, switch arm 28, wire 394, relay coil 30 and wire 395 to the other side of secondary 37. Energization of relay coil 30 moves switch arms 32 and 35 into engagement with contacts 34 and 36. Engagement of switch arm 35 with contact 36 energizes relay coil 134 of condenser pump relay 133 by a circuit as follows: hot line 375, wire 371, wire 380, wire 381, timer switch 82, wire 382, wire 427, contact 167 and switch arm 160 of summer-winter switch 163, wire 397, contact 36, switch arm 35, wire 398, switch arm 162 and contact 169 of summer-winter switch 163, wire 428, wire 429 and relay coil 134 to ground. Energization of relay coil 134 moves switch arm 136 into engagement with contact 35 to energize condenser pump 131 as follows: line 430, switch arm 136, contact 137, wire 431, condenser pump 131 and line 432. Operation of condenser pump 131 will produce a vacuum in condenser 130 and when this vacuum reaches approximately 26 inches of mercury the vacuum responsive switching mechanism 138 will allow mercury switch 141 to move to closed circuit position whereupon primary 56 of transformer 55 is energized as follows: hot line 375, wire 377, wire 380, wire 381, timer switch 82, wire 382, wire 427, contact 167, switch arm 160, wire 397, contact 36, switch arm 35, wire 398, switch arm 162, contact 169, wire 428, vacuum switch 141, wire 433, wire 400, low water cut off switch 57, wire 401, wire 402, and primary 56 to ground. Energization of transformer 55 results in opening of gas valve 18 provided the pilot switch 58-59 is closed and provided the steam pressure in boiler 14 is not excessive as heretofore explained in connection with the winter operation.

In the summer time, primary 101 of transformer 100 is constantly energized by a circuit as follows: hot line 375, wire 396, contact 164, wire 166, switch arm 161, contact 168, wire 434 and primary 101 to ground. Therefore, as soon as the steam pressure is built up to 13 lbs. to cause movement of pressure switching mechanism 104 to close its high pressure contacts, steam valve 98 will be energized to move the same to open position provided the temperature of steam jet injector is within predetermined limits which will be explained in more detail hereinafter. This energizing circuit for opening steam valve 98 is as follows: wire 435, the low temperature contacts of high temperature switching mechanism 106, wire 436, the high temperature contacts of the low temperature switching mechanism 105, wire 437, high pressure contacts of the pressure responsive switching mechanism 104 and wire 438, it being

noted that the secondary 99 of transformer 100 is constantly connected to valve 98 by wires 439 and 440. Opening of steam valve 98 allows steam to flow to the steam jet injector 61 by means of which the evaporator 441 thereof is cooled in a well-known manner. Opening of steam valve 98 also lifts lever 102 which carries mercury switch 103 whereby mercury switch 103 is moved to close position. Movement of mercury switch 103 to closed position energizes circulating pump relay 66, cooling tower circulating pump relay 148 and cooling tower blower relay 153. These circuits are as follows: hot line 375, wire 396, contact 164, wire 166, switch arm 161, contact 168, wire 434, wire 442, mercury switch 103, wire 443, at which point the circuit branches, one part going by way of wire 444 to relay coil 67 and to ground, whereas another portion continues by wire 445 to relay coils 149 and 154 and to ground. Energization of relay coil 67 moves switch arm 69 into engagement with contact 70 whereupon cooling circulating pump 65 is energized as follows: line 446, switch arm 69, contact 70, wire 447, pump 65, and line 448. Operation of this pump 65 circulates the cooling fluid through the evaporator 441 and to the cooling coil 60. Energization of relay coil 149 moves switch arm 151 into engagement with contact 152 and energizes this cooling tower water pump 144 as follows: line 449, switch arm 151, contact 152, wire 450, cooling tower pump 144 and wire 451. Energization of cooling tower pump 144 causes circulation of the condenser cooling water through the condenser cooling coil 142 and then to the water tower spray 143. Energization of relay coil 154 moves switch arm 156 into engagement with contact 157 whereupon cooling tower blower 147 is energized as follows: line 452, switch arm 156, contact 157, wire 453, cooling tower blower motor 147 and line 454.

In this manner, when the room becomes too warm in the summer and provided that the outdoor temperature is not below the desired room temperature, a proper vacuum is placed upon the steam jet injector and, when this proper vacuum is established, the gas valve 18 is energized to generate steam. When the steam pressure becomes sufficiently high, steam valve 98 is opened to supply steam to the steam jet injector and the various pumps and blowers are placed in operation. Delivery of steam to the steam jet injector causes the evaporator 441 thereof to become cool and this in turn cools the cooling fluid which is circulated to the cooling coil 60 by the circulating pump 65. The steam introduced to the steam jet injector 61 thereafter passes to condenser 130 where it is condensed and returned to the boiler by vacuum pump 131. The condensing operation is obtained by the usual condenser cooling coil 142 and the condenser cooling water may be used over and over since it is cooled by means of the water tower 145. The pump 144 serves to cause circulation of the condenser cooling water and, as heretofore explained, the water tower blower 147 provides an increased rate of evaporation so that the condenser cooling water is cooled more readily.

The air passing through air conditioning chamber 11 is therefore reduced in temperature in order to restore the room or space temperature to the desired value. The air passing into the air conditioning chamber 11 will be taken from the outdoors and from the building in amounts which are determined by the positions of inlet dampers 92 and 93 which are controlled in the manner

heretofore set forth in detail. Similarly, the air passing through air conditioning chamber 11 is delivered to the rooms and to the basement in accordance with the position of mixing damper 96 which is controlled by basement temperatures in a manner also fully explained heretofore.

If the steam is used up faster than it is being generated, pressure responsive switching mechanism 104 will return to the position shown in the drawings when the steam pressure falls to approximately 10 lbs. When this happens, the steam valve 98 is closed by a circuit as follows: wire 438, the low pressure contacts of pressure responsive switching mechanism 104 and wire 15 455. Movement of steam valve 98 to closed position will open mercury switch 103 whereupon the two circulating pumps and the cooling tower blower are deenergized. Upon the steam pressure returning to approximately 13 lbs., the steam valve 98 will again operate by the circuit above described.

It is possible that the temperature of the steam jet evaporator 441 may fall to some low value such as 40° F. At some point such as this, practically 25 no further cooling thereof can be obtained by the further supply of steam and if much further cooling were possible, the temperature would become below freezing value which would be undesirable inasmuch as it would require a special 30 cooling fluid in order to eliminate the possibility of freezing thereof and would also offer the possibility of freezing any spray water which might be delivered from spray 36. Therefore, if the evaporator temperature does fall to some low 35 degree such as 40° F. low temperature responsive switching mechanism 105 will move to the position opposite that shown in the drawings to complete a closing circuit for steam valve 98 as follows: wire 438, high pressure contacts of pressure 40 responsive switching mechanism 104, wire 437, wire 456, and wire 455. The cooling apparatus will therefore be rendered inoperative until the temperature of the evaporating chamber rises to some higher value say 45° F., whereupon the 45 opening circuit for steam valve 98 heretofore described will be reestablished.

If the steam jet injector should not function properly, resulting in steam backing up into the evaporator 441 so that the temperature thereof 50 becomes so high as to render it incapable of cooling the circulating cooling fluid, then high temperature contacts of high temperature responsive switching mechanism 106 will close to establish a closing circuit for the steam valve 98 as follows: 55 wire 438, high pressure contacts of pressure responsive switching mechanism 104, wire 437, high temperature contacts of low temperature responsive switching mechanism 105, wire 436, the high temperature contacts of high temperature responsive switching mechanism 106, wire 457 and wire 456 to wire 455. Steam valve 98 will therefore close and the cooling system rendered inoperative until the evaporator temperature returns to normal whereupon steam valve 98 will 60 again be opened by the opening circuit previously described.

It will therefore be seen that the operation of the cooling system in the summer time is completely checked for all conditions of improper 70 operation. The vacuum switch 141 assures that there is a proper vacuum in the steam system so that the steam jet injector will operate properly. The pressure responsive switching mechanism 104 prevents operation of the steam jet injector unless 75 the steam pressure is sufficiently high. The low

temperature responsive switching mechanism 105 prevents operation of the steam jet injector in the event the evaporator thereof becomes too cool and the high temperature responsive switching mechanism 106 likewise prevents operation of the steam jet injector in the event the temperature of its evaporator becomes too high. From a practical standpoint, the steam jet injector cannot be operated unless there is a proper vacuum since steam cannot be generated unless there is a proper vacuum. However, it may happen that the vacuum is less than the desired 26 inches of mercury and at the same time there may be sufficient steam pressure to cause opening of the steam valve 98. If it is desired to eliminate this remote possibility, the vacuum responsive switching mechanism 138 may be removed from in circuit with primary 56 of transformer 55 and placed in circuit with the steam valve 98, such a change requiring a double-ended mercury switch 20 rather than the single-ended mercury switch shown. Such a change in connections might have the further advantage of allowing the vacuum to be produced and steam pressure generated concurrently so that the proper vacuum 25 and the proper steam pressure would be established more quickly upon a demand for cooling by the room thermostat.

The outdoor thermostat 22 normally will not come into play in the operation of the system 30 but in the event the room temperature is slightly above that desired and there is a sudden fall in the outdoor temperature, then the thermostat 22 will prevent operation of the cooling means since it is evident that circulation of outdoor air will 35 soon restore the room temperature to that desired without resorting to operation of the cooling means.

At night, the system will be completely out of 40 operation since time switch 82 will open and the pressure responsive switching mechanism 78 is inoperative by reason of closure of manual valve 16. As heretofore explained in connection with 45 the winter operation, the time switch 82 is only used where the air conditioning system of the present invention is being utilized in conjunction with office buildings and the like. If the system of the present invention be applied to buildings or residences which are in continuous use and wherein it is desired to have full twenty-four hour 50 control, then the time switch 82 would be omitted.

From the foregoing description, it will be apparent that the present invention provides an all year around air conditioning system wherein the building is heated, cooled, and humidified as 55 necessary. It will further be noted that both in the summer and the winter a reasonable amount of outdoor fresh air is brought into the building whenever the outdoor temperature is such as to permit such operation. Furthermore, 60 the cooling means and the heating means are both operated by the same medium, that is, by steam. Furthermore, this steam is produced by a single boiler under the control of suitable controls, many of which serve the double function 65 of controlling both in summer and in winter. The system of the present invention further provides for many other novel features in its operation which have previously been brought out during the detailed description.

While a plurality of separate summer winter switches have been shown, it is to be understood that in actual practice these various summer winter switches could all be grouped together and operated by a single control handle. The 75

separation of these switches has been shown herein merely for convenience of illustration. It will also be apparent that the valve 16 could be an electrical valve controlled by a further part of the summer winter switching mechanism.

It will be obvious that many changes and rearrangements could be made in the system of the present invention without departing from the various novel features contained herein and we therefore intend to be limited only by the scope of the appended claims.

We claim:

1. An all-year air conditioning system of the class described, comprising, in combination, a steam heating device for heating a space, a steam jet injector type of cooling means for cooling said space, a steam boiler for supplying steam to said steam heating device and steam jet injector type of cooling means, thermostatic means in control 15 of the generation of steam by said boiler, means associated with said thermostatic means to selectively cause the generation of steam by said boiler upon either a rise or fall in temperature and means for selectively sending the steam generated by the boiler to said heating means or cooling means.

2. An all-year air conditioning system of the class described, comprising, in combination, a steam operated heating means for heating a space, a steam operated cooling means for cooling the space, a steam boiler for generating steam to operate said heating means or cooling means, a space temperature responsive thermostat, an outdoor temperature responsive thermostat, means 30 to place said space temperature responsive thermostat alone or to place both of said thermostats in control of said boiler, a steam valve in control of the flow of steam to said cooling means, and means for rendering said steam valve operative or inoperative.

3. In a temperature changing system, in combination, a temperature changer for changing the heat content of air adapted to be circulated to first and second spaces, damper means in control 45 of the flow of air to both of said spaces to simultaneously increase the flow of air to one of said spaces and decrease the flow of air to the other of said spaces, a thermostat responsive to the temperature of only one of said spaces in control of said damper means, and a thermostat responsive to the temperature of the other of said spaces in control of said temperature changer.

4. In a temperature changing system, in combination, a temperature changer for changing the heat content of a circulating fluid adapted to change the temperature of first and second spaces, a thermostat responsive to the temperature of one of said spaces in control of said temperature changer, circulation controlling means in control 55 of the respective flow of fluid to said two spaces to simultaneously increase the flow to one and decrease it to the other, a thermostat responsive to the temperature of the other of said spaces in control of said circulation controlling means, and means for reversing the operation of said circulation controlling means by said last mentioned thermostat.

5. An all-year temperature changing system 60 comprising, in combination, means for circulating outdoor air to a space, damper means movable from a first position in which minimum outdoor air is circulated to said space through a second position in which all outdoor air is circulated to said space and to a third position in

which minimum outdoor air is circulated to said space, an outdoor winter thermostat for controlling said damper means to move the same from said second position to one of said other positions upon a predetermined decrease in outdoor temperature and incapable of moving said damper means to the remaining position, an outdoor summer thermostat in control of said damper means for moving the same from its first position through its second position and to its third position upon a predetermined rise in the outdoor temperature, and means for selectively placing one or the other of said thermostats in control of said damper means.

6. In a temperature changing system for a space, in combination, a duct connecting said space to the outdoors, a damper pivoted therein and movable through approximately 180 angular degrees whereby upon movement of said damper from one of its extreme positions to its other extreme position the supply of outdoor air is increased from a minimum to a maximum and then decreased to a minimum, motor means connected to said damper, said motor means having a complete range of movement capable of moving said damper through said approximate 180 angular degrees, a first thermostat adapted to move said motor means through the larger part of its range, a second thermostat adapted to move said motor means through a substantially smaller part of its range, and means for selectively placing one or the other of said thermostats in control of said motor means.

7. A heating system of the class described, comprising, in combination, means for circulating outdoor air to a space to be heated, damper means in control of the circulation of said air, a first heater, a space thermostat in control thereof, a second heater, and outdoor temperature influenced thermostatic means in control of said damper means for reducing the supply of outdoor air and for rendering said second heater operative at a predetermined minimum outdoor temperature.

8. A heating system of the class described, comprising, in combination, means for controlling the circulation of outdoor air to a space, first and second heaters for heating said air, a space thermostat in control of said heaters, and outdoor temperature influenced means for reducing the supply of outdoor air and for conditioning one of said heaters for operation by said thermostat when the outdoor temperature falls to a predetermined value.

9. A heating system of the class described, comprising, in combination, a chamber, means for circulating air therethrough, a steam heater located in said chamber for heating the air circulated therethrough, a space thermostat in control of the supply of steam to said heater, a time control for rendering said circulating means inoperative at predetermined times, and a steam pressure responsive device for operating said circulating means when the pressure of the steam supplied to said heater rises to a predetermined value irrespective of the condition of said time control.

10. A heating system of the class described, comprising, in combination, a chamber, means for circulating air therethrough, a steam heater located in said chamber for heating the air therethrough, a space thermostat in control of the supply of steam to said heater, a time control for rendering said circulating means inoperative at predetermined times, and a steam pressure re-

- 5 sponsive device for operating said circulating means when the pressure of the steam supplied to said heater rises to a predetermined value irrespective of the condition of said time control, means for humidifying the air passing through said chamber, a humidity responsive device adapted to control said means, and connections for rendering said humidity responsive device operative whenever said circulating means is circulating air through said chamber.
- 10 11. A heating and cooling system, comprising, in combination, a boiler for generating steam, a space temperature responsive thermostatic means, an outdoor temperature responsive thermostatic means, means to place said space temperature responsive thermostatic means alone in control of said boiler to cause generation of steam upon space temperature fall or to place both said thermostatic means in control of said boiler to cause generation of steam upon rise in both space temperature and outdoor temperature, steam operated heating means, steam operated cooling means, and means to selectively operatively associate either said heating means or said cooling means with said boiler.
- 15 12. In a heating system, in combination, means for controlling the circulation of fresh air to a space to be heated, damper means in control of the flow of fresh air to the space, motor means to gradually position said damper means, means responsive to outdoor temperature in control of said motor means to cause movement of said damper means in a direction to reduce the flow of fresh air to said space upon fall in outdoor temperature, a heater to heat the air supplied to said space, an electrically operated valve in control of the flow of heating fluid to said heater, and a switch in control of said valve operated by said motor means.
- 20 13. An air conditioning system for a plurality of spaces, comprising in combination, air conditioning means including heating means, cooling means and means for delivering conditioned air to all of said spaces, means including means responsive to the temperature of the air in at least one of the spaces for controlling the operation of the heating means and cooling means and consequently the condition of the air delivered to all of the spaces, means responsive to the temperature of the air in another of said spaces for controlling the volume of conditioned air delivered to said other space, and means for reversing the controlling action of the last mentioned temperature responsive means.
- 25 14. In an air conditioning system, in combination, a conditioning chamber through which air is adapted to be passed for a conditioning action, means for conducting the air leaving said conditioning chamber to a space to be conditioned, means for conducting air from said space to said conditioning chamber, a fresh air duct for conducting fresh air to said conditioning chamber, a damper for controlling the supply of fresh air, a heater for heating the fresh air supply, and outdoor air temperature influenced thermostatic means for controlling said damper and said heater in a manner to reduce the supply of fresh air upon fall in outside temperature, and to place said heater in operation when the outside temperature falls to a predetermined value.
- 30 15. In an air conditioning system, a conditioning chamber, means for causing a flow of fresh air through said chamber, an air temperature changing device in said chamber, a damper for controlling the flow of air to said temperature
- 35 changing device, and thermostatic means influenced by the temperature of the fresh air for controlling said damper and said temperature changing device, said thermostatic means acting to place the temperature changing device out of operation only when the damper is opened to a predetermined extent.
- 40 16. In an all-year temperature changing system, means for circulating outdoor air to a space, damper means in control of the circulation of outdoor air to said space, motor means connected to said damper means for operating the damper means to vary the flow of outdoor air from a minimum to a maximum and then to a minimum when the motor means moves through its complete range in one direction, a first thermostat for moving said motor means through its complete range, a second thermostat for moving said motor means through only a portion of said range, and means for selectively placing said thermostats in control of said motor means.
- 45 17. In an all-year temperature changing system, means for circulating outdoor air to a space, damper means in control of the circulation of outdoor air to said space, motor means connected to said damper means for operating the damper means to vary the flow of outdoor air from a minimum to a maximum and then to a minimum when the motor means moves through its complete range in one direction, a first thermostat for moving said motor means through its complete range, a second thermostat for moving said motor means through only a portion of said range, means for varying the range through which one of said thermostats operates said motor means, and means for selectively placing said thermostats in control of said motor means.
- 50 18. In a system of the class described for controlling the condition of more than one zone, in combination, a condition changer for changing the condition of first and second zones to be controlled, control means for varying the effect of said condition changer upon both of said zones, said control means being arranged to increase the effect of said condition changer upon one of said zones while decreasing the effect of said condition changer upon the other of said zones and being incapable of placing said condition changer in operation, means responsive to the condition of one of said zones for controlling said condition changer, and means responsive to the condition of the other of said zones for controlling said control means.
- 55 19. In a system of the class described for controlling the temperature of more than one zone, in combination, a single temperature changer for changing the temperature of first and second zones to be controlled, control means for varying the effect of said temperature changer upon both of said zones, said control means being arranged to increase the effect of said temperature changer upon one of said zones while decreasing the effect of said temperature changer upon the other of said zones and being incapable of placing said temperature changer in operation, means responsive to the temperature of one of said zones for controlling said temperature changer, and means responsive to the temperature of the other of said zones for controlling said control means.
- 60 20. In an air conditioning system for controlling the condition of the air in more than one zone, in combination, a single conditioner for conditioning air supplied to first and second zones, flow control means for varying the proportions
- 65 70 75 80 85 90 95 100

of the air supplied to said zones, said flow control means being arranged to increase the flow of air to one of said zones while decreasing the flow of air to the other of said zones, means responsive to the condition of the air in said one of said zones for controlling said conditioner in a manner to maintain a predetermined condi-

tion of the air in said one zone, and means responsive to the condition of the air in the other of said zones for controlling said control means in a manner to maintain a predetermined condition of the air in said other zone.
